UNITED STATES PATENT OFFICE.

WILLIAM ANTHONY JONES, OF WEST NEW BRIGHTON, NEW YORK.

FAN.

Application filed April 3, 1919. Serial No. 287,273.

To all whom it may concern:

Be it known that I, WILLIAM ANTHONY JONES, a citizen of the United States, and resident of West New Brighton, county of 5 Richmond, and State of New York, have invented certain new and useful Improvements in Fans, of which the following is a specification.

My invention relates particularly to fans 10 which receive gas at one side and discharge it at the other side.

One object of the invention is an apparatus for inducing a draft and at the same time separating dust from the gases being 15 acted upon.

In many processes of manufacture it is desirable to obtain more draft than that which results from a chimney in order to cause gases to flow through passages 20 provided for them and through various heat absorbing apparatus.

It frequently happens that the products of combustion are charged with a quantity of fine dust which it is desired to separate 25 from the gases.

In the case of cement kilns the dust which is carried away by the waste gases is very valuable.

In the case of burning fine sizes of hard 30 coal the dust which is carried out of the stack is objectionable in the neighborhood.

Ordinary centrifugal fans receive gas at the center, parallel to the axis, and discharge it radially, which necessitates a right-angle 35 change of direction of the gases and makes it difficult to obtain a gradual decrease and increase of gas passage cross-sectional area with a corresponding gradual increase and decrease of gas velocity which conduces to 40 efficiency.

Ordinary disc fans operate on gas at widely different distances from the center, and it is impossible to have equally good efficiency at all points. Ordinary disc fans act 45 on the gas without imparting any considerable rotary motion to the gas and the axial motion which they impart to the gas is accompanied by a heavy axial thrust on the fan.

50 In the accompanying drawings, Figure 1 is a longitudinal section through the fan and casing. Figure 2 is an end view, partly in section on the line AA of Figure 1, of the discharge end of the casing. Figure 3 shows 55 a part view of the fan wheel. Figure 4 is a development of a cylindrical surface concen-

tric with the axis and shows the intersection of this surface with the blades of the fan and with the stationary guide vanes at each side of the fan. Fig. 5, is a plan view of my fan 60 connected to a settling chamber. Fig. 6, is a vertical view, partly in section, of the structure shown in Fig. 5. Fig. 7 is a part section through the fan casing and bearings and shows pipes for conveying a cooling medium for the bearings. Fig. 8 is a development of a cylindrical surface concentric with the axis and shows the intersection of this surface with the blades of the fan and with stationary guide vanes at each side of the 70 fan. Fig. 8 is like Fig. 4 except that an arrow, "ss", is shown to represent the path of a particle of dust, and arrows, "NP", are shown to represent pressures normal to the guide vanes and normal to the blades of the fan. 75 Fig. 9 is a part section on the line, "GG", through the outlet, "Q", for dust and shows a view in plan of the arrow, "ss".

Similar parts are referred to by similar letters throughout the several views. 80

Referring to the drawings: a fan wheel "a", provided with blades "b", is mounted on a shaft "c". A gear "d" is fastened to the fan wheel and is driven by pinion wheel "e" mounted on shaft "f" which extends outside 85 of the fan casing.

The fan casing is represented as made of an inlet part "g" and an outlet part "h". A conical shield "i", concentric with the inlet part "g" of the fan casing, shields the 90 central part of the fan wheel "a". A similar conical shield "j" shields the central part of the fan wheel at the other side in the outlet part "h".

The space "k", between the conical shield 95 "i" and the inlet part "g" of the casing, forms a passage of gradually decreasing cross-sectional area for gas as it approaches the fan wheel blades "b". Stationary guide vanes "l" in the space "k", between the conical shield "i" and the casing "g", determine the direction of flow of gas to the wheel. Similar stationary guide vanes "m", in the space "n", between the conical shield "j" and the casing "h", determine the direction of 100 flow of the gas as it leaves the blades of the wheel. Inclination of the stationary guide vanes "l" and "m", with respect to the axis, causes an axial thrust of the gases without 105 a corresponding axial thrust on the fan 110 wheel.

In addition to the outlet passage "n", a

second outlet passage "o", at a greater distance from the center, is represented for the discharge of dust. Also stationary vanes "Z" for determining direction of flow in outlet "o".

The shell "p", immediately outside of the wheel "a", is made slightly larger in diameter at the outlet side than at the inlet side of the wheel, to facilitate the concentration 10 of dust at the greater radius from the center, by the action of centrifugal force, and the discharge of this dust through the passage "o", together with an accompanying relatively small volume of gas.

15 The diameter of the fan wheel at the tip of the blades is also shown greater at the outlet side of the fan wheel for the same reason.

The passage "o" for dust leads to orifice 20 "Q", from which dust may be conducted to a settling chamber. In the settling chamber the velocity of the gas from the orifice "Q" may be reduced so that dust will be deposited, and this relatively small volume of gas 25 may then be led to the inlet end of the fan again.

Figs. 5 and 6 show a settling chamber, "cc", of circular form which is representative of one form of such a settling chamber. 30 In this representation, dust laden gas enters the settling chamber tangentially, from the outlet, "Q", maintaining a rotary motion of the gases within the chamber. Gases pass below the lower edge of a circular internal baffle and then flow upward to the top of the chamber from which they may be conducted by the pipe, "rr", to the inlet side of the fan. The slow velocity of the gases in the large chamber and the change in the 40 direction of their flow causes the dust, with which the gases are laden, to be deposited in the dust settling chamber. The conical bottom of the chamber facilitates the dust being drawn off through the valved opening, "vv".

45 In its passage through the fan, the pressure of the gas will be least at the fan wheel where the velocity of the gas will be greatest, that is to say, the pressure at "r", between the blades of the fan wheel, will be less than the pressure at "s", at the inlet, or at "f", at the outlet.

Ordinarily, therefore, it will be possible to cool the bearings "n" of the fan shaft "e" and pinion shaft "f" by allowing air to flow 50 to these bearings through pipes from the atmosphere external to the casing, and such air may be discharged into the space within the conical shields "i" and "j" from which it will flow through space "r" to mingle with the gases being acted upon by the fan.

Or, bearings may be cooled by water or by oil conducted to and from the bearings by suitable pipes "pp" and "qq", one arrangement of which is shown in Fig. 7.

55 A shield "w", attached to the fan wheel

and projecting within a flange "x" of the conical shield "i", is represented for retaining the oil used for lubricating gears "d" and "e".

The blades "b" of the fan wheel "a" are 70 represented in planes passing through the axis. This results in no end thrust on the fan wheel and in a relatively slow speed of fan wheel for a given velocity of gas.

By making the planes of the blades 75 oblique to the axis with a retreating angle "y", with reference to the planes of the blades shown, the speed of the fan wheel may be increased with the same velocity of gas. When oblique blades are used, there 80 is an axial thrust on the fan, less than that of an ordinary disc fan, but the higher speed permits a high speed motor to be direct-connected to the fan without the necessity of reduction gears, even for low velocities of gas.

The action of the fan in causing gas to flow from a lower pressure to a higher pressure is as follows. Rotation of the fan wheel draws gas away from the spaces between the stationary vanes at the inlet side of the fan wheel and reduces the pressure at that point and this in turn causes gases to flow between the stationary vanes, at the inlet side, to the fan wheel. The gradual decrease in cross section of gas passage area at the inlet side permits the gases to acquire a relatively high velocity as they reach the wheel without the formation of eddies. In this respect the action of the gas passage of 95 100 gradually decreasing cross section is like the action of a Venturi tube, the wheel of the fan being at the throat.

The efficiency of my invention is high because, like a Venturi tube, it is adapted to 105 convert pressure into velocity, at the inlet side, and velocity into pressure, at the outlet side, and also because in passing through the apparatus gas has a very short path and for only a small part of that short path is it at 110 high velocity. The first of these features reduces loss from eddies to a minimum and the second reduces loss from skin friction to a minimum.

The gradual increase in cross sectional 115 area of the gas passages from the outlet side of the wheel is also like a Venturi tube and effectively converts velocity into pressure.

The absence of axial thrust on the moving wheel also reduces loss and wear. The apparatus is particularly adapted for use as a vacuum cleaner. The thrust bearings of other vacuum cleaner fans wear out in a short time and the dust bags of such vacuum cleaners require frequent cleaning and 120 offer resistance to the passage of air.

The cross sectional area for gas flow at the wheel is even less than it appears at first glance being the difference in area of the circle of the body of the wheel and the area of 130

the circle of the inside of the casing, multiplied by the sine of the angle of inclination of the stationary vanes. This disregards the thickness of the blades of the 5 wheel.

As shown on the drawings the area of gas flow at the wheel, corresponding to the throat of a Venturi tube, is about one sixth of the area of gas flow at the inlet and at the outlet. If it is desired to handle gas against 10 about seven inches of water pressure, corresponding to a velocity head of 475 feet for air at normal temperature, then the gas velocity at the wheel would be about 175 feet 15 per second and the velocity of the blades of the wheel would be about 125 feet per second. Of course the proportions are varied to suit conditions.

In the conditions assumed above the velocity at the inlet would be about one sixth the 20 velocity at the wheel, or about 29 feet per second, 1750 feet per minute.

The fact that, disregarding friction, the sum of the dynamic head and the pressure 25 head is a constant in a Venturi tube is the basis of the Venturi meter, where the decrease in pressure head at the throat, where the velocity is highest, is used to calculate the velocity of flow.

30 In the ordinary Venturi tube the final pressure is slightly less than the initial pressure due to friction.

In my invention the blades of the fan wheel add to the velocity at the throat so 35 that the final pressure is greater than the initial pressure.

The fact that the energy of motion is as the square of the velocity, makes it necessary to add only a small amount to the relatively 40 high velocity, which the gas has when it reaches the wheel, in order to add sufficient kinetic energy to the gas to enable it to enter the higher pressure at the outlet of the fan. This relatively small increase in velocity is 45 evidently accompanied with much less disturbance and loss in eddies and impact than when the blades of a fan wheel bite into stationary gas or gas flowing slowly in passage ways of relatively large cross sectional area, 50 so that adjacent parts of the gas are suddenly torn away at high velocity.

With the proportions shown on the drawings and described above, in my invention, the blades of the fan wheel practically exert 55 a pressure on the swiftly moving gas, urging it forward, without such an abrupt change in velocity.

The action of separating dust and dust laden gas from gas which is free from dust 60 may be analyzed as follows:

The arrow, "ss", Figs. 7, 8, and 9, represents the direction and velocity of a particle of dust which is being carried by gas entering the inlet side of the fan. This particle 65 of dust is as near the center as possible and

is moving tangentially to the conical shield and also in the direction of the stationary guide vane which is next to this particle of dust. By reason of its inertia, the particle of dust will tend to move forward in this 70 direction in a straight line and in a given interval of time its distance from the axis of the fan will increase from R^1 to R^2 . During this interval of time its transverse motion will be equal to the length of the line, 75 L^s , and its longitudinal motion will be equal to the length of the line, L^2 . Evidently with the relative proportions shown, the direction of motion of this particle of dust will carry it into the outlet for dust, "o". 80

Evidently if the angle of the cone were less without increasing the width of the wheel or the wheel were made narrower without increasing the angle of the cone, then the direction of motion of this particle of dust, which is tangent to the cone, would not carry the particle into the opening, "o", for dust. Again this object would not be attained if the diameter of the base of the cone were made smaller without making corresponding changes in the other dimensions of the fan.

The above shows that, with the proportions shown, the particle of dust next to the conical shield at the inlet side of the fan will 95 be carried to the outlet for dust, "o". Evidently all other particles of dust which are initially at a greater distance from the axis of the fan, will have a less radial distance to go and will also be carried to the outlet for 100 dust, "o".

The particular arrangement shown may be altered without departing from principle of the invention.

Having described my invention, what I 105 claim as new and desire to secure by Letters Patent is:

1. In apparatus for causing gas to flow from a lower pressure to a higher pressure, the combination of a shaft with bearings, a 110 fan wheel with blades, a casing having a concentric conical shield at the inlet side of the fan wheel, and a second concentric conical shield at the outlet side of the fan wheel, stationary vanes, oblique to the axis, between the conical shields and the shell of the casing, an inlet for gas at one side of the fan wheel, an outlet for gas at the other side of the fan wheel, a second outlet for dust at a greater distance from the center 115 than the first outlet, stationary vanes for determining the direction of flow of dust from the fan wheel blades to the second outlet, passages for conducting a cooling medium to the bearings. 120

2. In apparatus for causing gas to flow from a lower pressure to a higher pressure, the combination of a shaft with bearings, a fan wheel with blades, a casing having a 125 concentric conical shield at the inlet side of 130

the fan wheel, and a second concentric conical shield at the outlet side of the fan wheel, stationary vanes, oblique to the axis, between the conical shields and the shell of the casing, an inlet for gas at one side of the fan wheel, an outlet for gas at the other side of the fan wheel, a second outlet for dust at a greater distance from the center than the first outlet, stationary vanes for determining the direction of flow of dust from the fan wheel blades to the second outlet.

3. In apparatus for causing gas to flow from a lower pressure to a higher pressure, the combination of a shaft with bearings, a fan wheel with blades, a casing having a concentric conical shield at the inlet side of the fan wheel, and a second concentric conical shield at the outlet side of the fan wheel, stationary vanes, oblique to the axis, between the conical shields and the shell of the casing, an inlet for gas at one side of the fan wheel, an outlet for gas at the other side of the fan wheel, a second outlet for dust at a greater distance from the center than the first outlet.

4. In apparatus for causing gas to flow from a lower pressure to a higher pressure, the combination of a fan wheel with blades, a casing having a conical shield at the inlet side of the fan wheel, a second conical shield at the outlet side of the fan wheel, stationary vanes between the conical shields and the shell of the casing, the cross sectional area for flow of gas being least at the fan wheel and gradually increasing at each side of the fan wheel, substantially as described.

5. In apparatus for causing gas to flow from a lower pressure to a higher pressure, the combination of a fan wheel with blades, a casing having a conical shield at the inlet side of the fan wheel, a second conical shield at the outlet side of the wheel, stationary vanes between the conical shields and the casing, with the vanes curved so that they are oblique to the axis near the fan wheel and are parallel to the axis at the point farthest from the fan wheel, the cross sectional area for flow of gas being least at the fan wheel and gradually increasing at each side.

6. In apparatus for causing gas to flow from a lower pressure to a higher pressure, the combination of a shaft with bearings, a fan wheel with blades, a casing having a concentric conical shield at the inlet side of the fan wheel, and a second concentric conical shield at the outlet side of the fan wheel, stationary vanes, oblique to the axis, between the conical shields and the shell of the casing, an inlet for gas at one side of the fan wheel, an outlet for gas at the other side of

the fan wheel, a second outlet for dust at a greater distance from the center than the first outlet, a chamber for settling dust, a connection from the outlet for dust to the chamber for settling dust, a connection for returning gas from the chamber for settling dust to the inlet of the fan.

7. In apparatus for causing gas to flow from a lower pressure to a higher pressure, the combination of a fan wheel with blades, a casing, a conical shield at the inlet side of the fan wheel, a second conical shield at the outlet side of the fan wheel, stationary vanes, oblique to the axis, between the conical shields and the casing, all so that rotation of the fan wheel causes rotation of the gas at the fan wheel and the oblique stationary vanes cause an axial thrust on the gas, the cross sectional area for flow of gas being least at the fan wheel where the velocity of gas is greatest, substantially as described.

8. In apparatus for causing gas to flow from a lower pressure to a higher pressure, the combination of a fan wheel with blades whose surfaces are formed of lines which are parallel to the axis of the fan wheel so that a pressure normal to the surfaces will not cause an axial thrust on the fan wheel, a casing, a conical shield at the inlet side of the fan wheel, a second conical shield at the outlet side of the fan wheel, stationary vanes, oblique to the axis, between the conical shields and the casing, all so that rotation of the fan wheel causes rotation of the gas at the fan wheel and the oblique stationary vanes cause an axial thrust on the gas, the cross sectional area for flow of gas being least at the fan wheel where the velocity of the gas is greatest, substantially as described.

9. In apparatus for causing gas to flow from a lower pressure to a higher pressure, the combination of a shaft with bearings, a fan wheel with blades, a casing having a concentric conical shield at the inlet side of the fan wheel, and a second concentric conical shield at the outlet side of the fan wheel, stationary vanes, oblique to the axis, between the conical shields and the shell of the casing, an inlet for gas at one side of the fan wheel, an outlet for gas at the other side of the fan wheel, a second outlet for dust at a greater distance from the center than the first outlet, a chamber for settling dust, a connection from the outlet for dust to the chamber for settling dust.
